LOUD SPEAKER MOUNTING

Frederick P. Bartlett, Chicago, Ill., assignor to
The Magnavox Company, Chicago, Ill., a cor-
poration of Arizona

Application January 30, 1932. Serial No. 589,883

4 Claims. (Cl. 179—146)

My present invention relates to loud speakers such as are used with radio sets, phonographs and the like for reproducing sound and more particularly to a novel improvement whereby a 5 loud speaker, its transformer and/or other accessories can be conveniently and securely mounted upon a panel or partition by a single securing means.

The object of my invention is to provide a 10 simple, inexpensive and novel form of mounting for a loud speaker.

A further object of my invention is to produce a loud speaker structure which can be easily and securely mounted upon any bulkhead or other 15 partition.

Another object of my invention is to provide a novel means for mounting a loud speaker beneath the cowl of an automobile body upon the thin sheet metal partition.

20 In mounting a loud speaker, of the type contemplated by my invention, upon a partition or the like it has been customary to recess the loud speaker in the partition. This is generally accomplished by cutting a large hole in the partition and securing the loud speaker to the partition at its rim adjacent the periphery of the diaphragm. With such a mounting it is necessary to use a number of screws or other securing means at equally spaced points around the diaphragm and unless the partition or baffle is relatively stiff and rigid the weight of the speaker, which is greatest at a point some distance from the rim of the diaphragm, will have a tendency to break away from its support. It is therefore a 35 further object of my invention to provide a securing means for mounting a loud speaker which will place the heaviest part of the speaker close to the supporting partition and thereby greatly reduce the strain upon the securing means. This 40 type of mounting will be found of particular advantage in mounting loud speakers where the installation is subject to vibration and jolting, as when the speaker is installed upon the thin metal dash of an automobile body.

45 When a loud speaker is secured upon a partition in accordance with prior art practice the partition serves as a baffle to prevent the sound waves produced at the front of the diaphragm from combining with the sound waves emanating 50 from the back of the diaphragm and thus causing a distortion of the sound. Therefore, it may be said that another object of my invention is to provide a novel form of baffle means for a loud speaker which is not recessed in a partition or 55 other similar form of baffle.

For a better understanding of my invention reference should be had to the accompanying drawing wherein I have shown by way of illustration and not of limitation preferred embodiments thereof.

60 In the drawing wherein like numerals refer to like parts throughout the several views;

Figure 1 is a vertical view partially in section showing one form of my invention,

Figure 2 is a view similar to Figure 1, showing 65 another form of my invention,

Figure 3 is a vertical view showing my improved baffle in section,

Figure 4 is a fragmentary view partially in 70 section showing the manner of mounting a loud speaker in an automobile in accordance with my invention, and

Figure 5 is a modified form of my invention.

In the drawing 10 designates a magnetic field frame of pot like construction. The frame 75 can be of any shape. It is illustrated in the form most commonly used. The frame 10 carries the usual annular pole piece 11 to which there is attached a diaphragm housing or support 12. A conical diaphragm 13 which is secured at its rim to the support 12 has an actuating coil at its apex that is disposed in cooperating relation with the magnetic field structure.

80 Within the frame 10 there is provided a central or inner pole piece 14. One end of this pole piece 14 is disposed in spaced relation with an opening in the pole piece 11 to provide an annular air gap in which the diaphragm actuating coil is located. The other end of the pole piece 14 is usually projected through the frame 10 and 90 riveted or peened over to secure it in place.

In the past, in a mounted speaker of the above type, it has been the practice to secure the loud speaker at the rim of the housing 12 to a suitable supporting baffle.

95 This form of mounting is very satisfactory in radio cabinets, etc., where the apparatus is not subject to any substantial amount of vibration or jarring but when a mounting of this character is used it has been found necessary, particularly 100 with a large speaker, to provide an additional foot or support at the back of the field frame 10 in order to relieve the strain upon the securing screws which engage the baffle.

105 It is well known that the heaviest part of a dynamic loud speaker is the field frame. In loud speakers of this type it is customary to mount the input transformer upon the field frame and this practice further adds to the weight of the speaker at this point. This heaviest part of 110

the speaker, due to the depth of the cone, is located some distance from the rim of the diaphragm and support and as a result the heavy weight of the field magnet and transformer tends to pull the diaphragm housing away from the supporting baffle, unless a support or foot is placed thereunder as suggested above.

There are also installations in which it is impractical to mount a loud speaker where the supporting partition can act as a baffle. Sometimes it is impossible to cut a large enough opening in the partition and at other times the particular partition is not suitable for this type of mounting. An example of this latter case is where it is desired to mount the speaker upon the bulkhead which divides the engine compartment from the body of an automobile. The bulkhead referred to is usually of thin sheet iron which is not sufficiently rigid to properly support the speaker. An objection to the prevailing form of mounting in this latter position is also due to the fact that it is not good practice to expose the speaker to the grease and oil which usually collects under the hood of an automobile.

In one embodiment of my invention, in order to overcome the above objection, I provide the field frame with a centrally disposed threaded stud 15 which extends rearwardly so that it may be projected through the partition 17 to secure the speaker thereupon.

In Figure 1 of the drawing the stud 15 is shown as threaded into the end of the inner pole piece or core 14 and in Figure 2 the stud 15 is illustrated as formed integrally with the core 14. The stud 15 is threaded on its end and a nut 16 is threaded thereupon so that when the stud is projected through a partition 17, as shown, the speaker can be firmly clamped in place.

Cooperating with the stud 15, as illustrated in the above figures of the drawing, there is provided between the frame 10 and the partition 17 a relatively large washer 18. This washer 18 may be made of wood, fibre or other yielding material which will compensate for any irregularity in the surface of the frame 10 or partition 17 and afford a firm engagement.

A second relatively large washer 19 is also supplied when the partition 17 is of thin flexible material. This washer serves to stiffen the partition at this point and prevents a bending thereof under the weight of the speaker.

It is appreciated that this form of mounting does not permit the partition 17 to act as a baffle for the diaphragm 13 and therefore some other form of baffle must be provided. The baffles now most commonly used with this type of speaker project out from the rim of the diaphragm in a plane at right angles to its axis of movement.

As suggested above, it is impractical to mount a baffle of the above type under the cowl of an automobile body and many other like points and therefore I provide a novel baffle which can be disposed around the speaker in an effective manner.

In Figure 3, I show one type of baffle which can be formed by a cylindrical member 20 secured to the rim of the speaker support 12 so as to project rearwardly of the diaphragm and terminate in spaced relation with the partition 17. While this baffle member 20 is illustrated as cylindrical, it is to be understood that it may take other shapes, for example it may be square or conical in form.

In connection with this form of baffle it should be stated that others have mounted dynamic

speakers in a box and then secured the box upon the partition. Such an arrangement seriously interferes with free movement of the air from the rear of the diaphragm, sets up compressional waves and prevents the efficient operation of the speaker. The present arrangement distinguishes from the above practice in that the baffle is completely out of contact with the partition 17 and therefore affords sufficient freedom for the movement of the air at the rear of the diaphragm.

In this figure of the drawing the speaker frame 10 is shown as carrying an input transformer 21 and a terminal block 22 upon which the ends of the several conductors of the speaker terminate. The terminal block 22 is shown as provided with a protecting cover 23.

A further modification of my invention is illustrated in Figure 5 of the drawing. In this embodiment I dispense with the stud 15 and project the pot like frame 10 through the partition 17. The frame 10 is then secured in place by screws 24. With this form of mounting the weight of the speaker is practically balanced on the partition. This arrangement brings the rim of the diaphragm support 12 nearer the supporting partition 17 and therefore, in order to provide additional air space behind the diaphragm I may, if necessary, provide a conical baffle 25, as shown.

From the above description it will be clear that, in addition to providing a new and novel mounting, I have provided a mounting for loud speakers of the electro-dynamic type which will bring the parts of the speaker of greatest weight near the point of support. This arrangement completely eliminates the possibility of the speaker being dislodged from its mounting when subjected to any vibration or violent jolting.

While I have, for the sake of clearness and in order to disclose my invention so that the same can be readily understood, described and illustrated specific devices and arrangements, I desire to have it understood that this invention is not limited to the specific means disclosed but may be embodied in other ways that will suggest themselves to persons skilled in the art. It is believed that this invention is new and all such embodiments as come within the scope of the appended claims are to be considered as part of this invention.

Having thus described my invention, what I claim and desire to secure by Letters Patent is—

1. In an electro-dynamic loud speaker suitable for mounting upon a vertically disposed partition, the combination of an electro-magnetic field frame having a diaphragm mounted upon one end thereof, a single stud extending rearwardly from said field frame adapted to project through the partition, a yielding member between the speaker frame and one side of the partition, a relatively large washer of stiff material on the other side of the partition, and means upon the end of said stud for securing said yielding member and said washer in clamping engagement with the partition to thereby secure the speaker thereupon.

2. In a loud speaker of the electro-dynamic type having a conical diaphragm, the combination of a means upon the speaker frame for securing it against a surface with the diaphragm projecting outwardly therefrom so that said surface will not act as a baffle, and a truncated conical baffle secured at the rim of the diaphragm projecting toward and held in spaced relation with said surface.

3. In a loud speaker of the electro-dynamic type, the combination of a magnetic field frame, a central pole for said field frame having a reduced end which is peened over to secure it upon said field frame, and a threaded extension projecting through the peened over portion of said central pole and providing a sole means for securing the loud speaker upon a non-baffle forming surface.

4. In sound reproducing apparatus, the combination of a loud speaker having a magnetic

field frame, a conical diaphragm mounted in operative relation upon one end of said field frame, means carried by said field frame for securing it against a non-baffle forming surface, and a truncated conical baffle member secured at the rim of said diaphragm and projecting rearwardly over the diaphragm with its free edge out of contact with said non-baffle forming surface.
